(57) **CLAIM**

The ornamental design for a holder with flexible receiver for retaining a cleaning substrate, as shown and described.

DESCRIPTION

FIG. 1 is an isometric view of the holder with flexible receiver for retaining a cleaning substrate in a first configuration.

FIG. 2 is a side view of the holder with flexible receiver for retaining a cleaning substrate of FIG. 1.

FIG. 3 is an opposite side view of the holder with flexible receiver for retaining a cleaning substrate of FIG. 1.

FIG. 4 is a front view of the holder with flexible receiver for retaining a cleaning substrate of FIG. 1.

FIG. 5 is a rear view of the holder with flexible receiver for retaining a cleaning substrate of FIG. 1.

FIG. 6 is a top view of the holder with flexible receiver for retaining a cleaning substrate of FIG. 1.

FIG. 7 is a bottom view of the holder with flexible receiver for retaining a cleaning substrate of FIG. 1; and,

FIG. 8 is a side view of the holder with flexible receiver for retaining a cleaning substrate in a second configuration.

1 Claim, 8 Drawing Sheets
